UNITED STATES PATENT OFFICE.

JOHN C. SPENCER, OF SPICELAND, INDIANA.

SHADE-ROLLER CONTROLLING MEANS

Application filed November 14, 1921. Serial No. 515,080.

To all whom it may concern:

Be it known that I, JOHN C. SPENCER, a citizen of the United States, residing at Spiceland, in the county of Henry and State 5 of Indiana, have invented certain new and useful Improvements in Shade-Roller Controlling Means, of which the following is a specification, reference being had to the accompanying drawings.

10 This invention relates to window shade fixtures and more particularly to means for controlling the movement of a shade roller.

It is an object of the invention to provide means of this character which permits an 15 operator to regulate the rotation of the shade roller by the spring so that the shade may instantly be adjusted and held exactly at the point desired.

It is also an object of the invention to 20 provide means of this character which eliminates the usual ratchet and pawl mechanism formerly carried by the roller and provides a spring pressed pawl which is carried by the support of the roller or 25 bracket, said pawl being manually controlled by a lever positioned centrally of the roller.

It is a further object of the invention to 30 provide means of this character including a movable support to which shade brackets are connected, the shade brackets supporting the usual spring operated shade roller, a pawl mechanism carried by one of said brackets for engagement with the shade 35 roller, and a handle and a trigger carried by the movable support in spaced relation to the pawl mechanism for releasing and stopping the rotation of the shade roller when desired in the adjustment of the curtain, and wherein said pawl mechanism provides a positive locking device which prevents accidental rotation of the roller.

40 It is still a further object of the invention to provide means of this character including a shade having a rod secured to one end to which a curtain or shade cord is detachably mounted, the cord serving to support the shade over the window, the opposite end of the curtain or shade being 45 connected to a roller carried by a movable support, whereby the length of the shade may be increased or decreased by operation of the roller, and the window shade in its 50 adjusted position moved longitudinally of 55 the window by the curtain cord.

With these and other objects in view, the

invention consists in the improved construction and arrangement of parts to be herein-after more particularly described, fully claimed and illustrated in the accompanying drawings, in which:

Figure 1 is a view in elevation of a window shade showing the controlling means applied;

Figure 2 is a side elevation of the structure 65 shown in Figure 1;

Figure 3 is a plan view of the controlling means, the shade being removed;

Figure 4 is a section taken on the line 70 4-4 of Figure 3; and

Figure 5 is a detailed view of the collar or drum, by means of which the rotation of the shade roller is controlled.

Referring to the drawings, 9 designates 75 a supporting member of any desired material, such as a wooden or metal bar. Secured to each end portion of the bar and projecting at right angles to said bar are shade brackets 10 and 11. It is of course obvious that these brackets may be adjusted 80 longitudinally of the bar to accommodate the size of the shade roller. The bracket 11 has a substantially rectangular slot 12, while the bracket 10 has a substantially circular opening 13. A shade roller 14 of conventional form is adapted to be supported by the brackets 10 and 11, said roller including the usual hollow end portion 15. Disposed within said hollow end portion is a spring 16. A pintle or trunnion 18 projects 85 from the end portion 15, said pintle being substantially flat or rectangular and adapted to extend through the slot 12. The pintle is secured or connected to a shaft 19 around which the spring 16 is wound so as 90 to permit rotation of the roller 14 independently of the pintle. The end portion 15 is provided with an opening 20 adapted to register with an opening 22 carried by the pintle 18 so that when the shade is being 95 attached to the roller, a nail or like implement may be inserted in said openings. The nail is removed when the roller is engaged with the brackets, to permit rotation of the spring and is inserted in said openings to 100 prevent rotation of the spring when the roller is removed from the brackets.

Carried by the opposite end 23 of the roller is a cap or ferrule 24, while extending from said end of the roller is a stub 110 shaft 25. The shaft 25 has its end portion 26 substantially flattened and inserted in

the end 23 of the roller. A nail 27 or like fastening means is inserted through the ferrule and through an opening 28 provided in the end portion 26 of the stub shaft to prevent rotation of said shaft independently of the roller. The end portion 29 of the stub shaft is substantially round so as to permit rotation of the shaft relative to the bracket 10, while disposed adjacent the end portion 10 29 of the stub shaft is a collar or drum 30 having a plurality of openings or recesses 31 in its periphery. It will thus be seen that by this arrangement the pintle 18 is prevented from rotation, while the stub shaft 15 25 is adapted to rotate with the roller.

In order to render the locking action and the adjustment of the shade roller more positive and accurate than was possible heretofore, there is provided a novel controlling mechanism comprising a casing 32 which is secured to the inner face of the outwardly projecting arm or bracket 10, the ends of the casing being open. A longitudinally extending slot 33 is also provided in the upper portion of the casing, or that portion of the casing which is disposed flush with the upper edge of the bracket 10. Slidably mounted in the casing is a pawl 34, said pawl having one end reduced to provide a tooth 35 and having a transversely extending threaded opening 36 in its intermediate portion adapted to receive a stud or finger 37. The stud or finger 37 is adapted to project through the slot 33, while a tooth 35 is 35 adapted to project through the forward end of the casing and into one of the openings 31 so as to control movement of the roller 14. Disposed between the end of the bracket secured to the support and the rear 40 end of the pawl 34 is a coil spring 38. By disposing the casing 32 adjacent the foot or end of the bracket 10 it is not necessary to close the rear end of the casing, as it is possible for the spring to engage the bracket. 45 The spring is intended to normally urge the pawl outwardly of the forward end of the casing into engagement with the collar or drum 30.

In order to manually control the operation of the pawl without requiring the operator to go to the end of the roller to adjust said pawl, there is provided a handle member 39 which is secured to the intermediate portion of the movable support 9 substantially in a horizontal position, said handle being stationary or rigid. Pivoted to the handle 39 is a trigger 40 adapted to move laterally of the handle and having an opening 41 in its upper end. Pivoted to the 60 top of the support 9 adjacent the foot of the bracket is a bell crank lever 42, the end 43 of said lever being connected by a connecting member 44 to the trigger 40, said connecting member extending through the opening 41. The end 45 of the bell crank

lever is connected by a link 46 to the stud 37 of the pawl, said link extending over the foot of the bracket.

The opposite end of the shade is provided with a pocket 47 in which a reinforcing strip 70 or bar 48 is disposed, the strip being preferably rectangular in cross section. A balancing cord 49 is secured at its ends to the bar 48, the securing means being protected and covered by clips 50. A curtain cord 51 has 75 one end formed into a loop 52 adapted to engage the balancing cord 49, said loop being slidably longitudinally of the cord 49 so as to balance the shade upon adjustment of the cord 51 by the operator. 80

The cord 51 is arranged to extend over a lock pulley 53 of conventional form, said pulley being carried by the upper portion of the window casing so that when desired the cord may be locked in the pulley to hold 85 the shade in the desired adjusted position.

In operation, when it is desired to adjust the shade over the window, the cord 51 may be released from its locked position and the entire shade including the roller and the 90 support moved longitudinally of the window to the point desired. If the shade is not long enough, it may be readily adjusted by grasping the handle 39 and operating the trigger 40 so as to cause release of the pawl 95 34 and permit the shade roller to rotate through the medium of the spring 19. This adjustment may be made without releasing the curtain cord 51. When the trigger 40 is released the roller is instantly locked and 100 prevented from accidental rotation regardless of the movement of the shade by the cord 51.

From the foregoing it will be readily seen that this invention provides novel means 105 for controlling a shade roller which may be operated independently of the curtain cord of the shade to decrease or increase the length of the shade and wherein the roller may be moved bodily with the support and 110 curtain by the curtain cord. In addition to this, the support of the brackets is also utilized to carry a part of the controlling mechanism. It is therefore possible to position the trigger for operating said mechanism centrally of the shade roller and within 115 conveniently reach of the operator so that the shade roller may be instantly adjusted. Furthermore the possibility of vibration causing accidental rotation of the roller is 120 eliminated.

What is claimed is:—

1. A shade fixture of the character described embodying a support arranged to move longitudinally of a window casing, 125 brackets carried by and projecting outwardly from the support, a spring actuated shade roller mounted between the brackets, a spring pressed pawl carried by one of said brackets adjacent one end of the roller, a 130

handle member projecting from the intermediate portion of the support, a trigger carried by said handle, and means operatively connecting the trigger to the spring 5 pressed pawl for releasing the pawl and permitting rotation of the roller through the medium of the spring.

2. Means for controlling the movement of a shade roller embodying a movable support, brackets projecting from said support, a shade roller rotatably mounted upon said brackets, a casing carried by the inner face of one of said brackets, a pawl disposed within said casing, a finger carried by said 15 pawl and projecting through the slot pro-

vided in said casing, a spring disposed between said pawl and the foot of said shade bracket, said pawl being adapted to operatively engage a ratchet member carried by one end of the roller, a bell crank lever carried by the support adjacent the pawl, a handle member secured to the support, a trigger pivoted to said handle member, and means for operatively connecting the pawl to one end of the bell crank lever and the 20 opposite end of the bell crank lever to the trigger.

In testimony whereof I hereunto affix my signature.

JOHN C. SPENCER.
